(57) **CLAIM**

The ornamental design for a microvolume sample plate, substantially as shown and described.

DESCRIPTION

FIG. 1 is a top perspective view of a microvolume sample plate, showing our new design;

FIG. 2 is a bottom perspective view thereof;

FIG. 3 is an enlarged bottom perspective view thereof, showing a corner portion of the plate;

FIG. 4 is a top plan view thereof;

FIG. 5 is a bottom plan view thereof; and,

FIG. 6 is an enlarged view of the bottom plan thereof, showing one of the bottom pattern detail as seen in FIGS. 2 and 5.
